UNITED STATES PATENT OFFICE.

RAYMOND S. WILE, OF PITTSBURGH, PENNSYLVANIA.

APPARATUS FOR REDUCING ORES.

1,111,050.

Specification of Letters Patent. Patented Sept. 22, 1914.

Original application filed December 15, 1913, Serial No. 806,692. Divided and this application filed February 3, 1914. Serial No. 816,194.

To all whom it may concern:

Be it known that I, RAYMOND S. WILE, a citizen of the United States, residing at Pittsburgh, in the county of Allegheny and State of Pennsylvania, have invented a new and useful Improvement in Apparatus for Reducing Ores, of which the following is a full, clear, and exact description, reference being had to the accompanying drawings, forming part of this specification, in which the figure is a vertical section of one form of apparatus embodying my invention.

My invention relates to the reduction of ores, and is designed to provide a novel construction and arrangement of electric furnace in which ores may be reduced to mattes, metals or other elements or compounds in a cheap and efficient manner.

The present invention is a division of my pending application Serial No. 806,692, filed December 15, 1913.

One object of my invention lies in doing away with the difficulty arising in such furnaces, owing to the varying resistance in the coke, charcoal, or other fuel surrounding the electrodes.

Another object is to retard the rapid destruction of the electrodes and their breaking.

30 A still further object is to obtain a more uniform heat and consequently more regular action of the furnace.

Heretofore, in such furnaces, particularly those used for iron smelting, for which my invention is particularly designed, the shaft or stack portion of the furnace is provided with an enlarged crucible at its lower end into which the charge descends. The electrodes project in through the roof or sides of this crucible and coke or charcoal is packed around or between them. With such apparatus, the heat is uneven, due to the variation in the carbon resistance near the electrodes. The wear on the electrodes is rapid and severe and they are liable to break. Also there is chemical action between the charge and the electrodes which project a considerable distance into the crucible. I avoid these difficulties by providing a furnace with a relatively deep crucible adapted to hold a deep bath of molten slag, the crucible being enlarged to cross sec-

tional area with respect to the stack portion of the furnace through which the charged material is fed; and I so arrange the upper 55 electrodes that they will contact with the upper portion of the slag bath while being out of contact with the charge. No packing of coke or charcoal is needed around the electrodes, because the heat is generated in 60 the slag. This heat is, therefore, much more uniform. The wear on the electrodes is greatly reduced, and uniform action of the furnace is obtained.

In the drawings, in which I show one 65 form of furnace embodying my invention, 2 represents the shaft or stack portion of the furnace, which may be of any desirable type, and 3 the enlarged crucible into which the charge descends from the stack. I have 70 shown three electrodes, the upper two 4, 4, of which project in through holes in the roof of the crucible and may be adjusted by the rack-and-pinion mechanism shown at 5. The lower electrode 6 projects through the bottom of the crucible and contacts with the reduced material. Any number of electrodes may, of course, be used, either in the top or the bottom.

I may employ different types of electric 80 current. For example, in the form shown, I may use a three-phase current, one phase connected to each electrode, or I may use a two-phase current, the upper electrodes being each connected to one phase and the lower electrode to a common return conductor.

In the upper part of the crucible, near its connection with the shaft, is provided a slag outlet 7, and a tap-hole 8 is provided 90 for the reduced material from the bottom through the side of the crucible. Twyers 9 are provided in the bosh of the shaft through which air may be blown in, if desired to burn the carbon-monoxid rising 95 from the charge of ore, coke or other fuel and flux.

In starting the furnace, I first lower the upper electrodes until they contact with some conducting material in the bottom of 100 the crucible, so that the current will flow and melt this material. The slag-forming material is gradually filled in and the electrodes gradually raised until the crucible is

practically full of molten slag bath. The charge in the stack descends into this bath as reduction occurs, and the reduction continues through the stack and crucible. The 5 molten reduced material collects at the bottom of the crucible, where it is tapped off in the usual manner, the heat being obtained by the resistance from the current passing, at least, partially, in a vertical direction 10 through the deep slag bath. As the slag increases, it is tapped off through the slag hole at the top of the crucible to keep the bath at a practically constant depth.

As the upper electrodes enter the crucible, 15 only a small distance, they are subjected to the gases to only a slight extent, and hence their life is relatively long. The charge material descending into the bath does not contact with them, and hence there is no 20 chemical action between the two and no pressure from the charge on the electrodes tending to break them.

Little manipulation of the electrodes is required as they will wear very slowly. The 25 operation goes on continuously, the charge being supplied at the top of the stack and the reduced material being tapped out at the bottom of the crucible.

The advantages of my invention result 30 from the provision of a furnace having a relatively deep crucible and in which the electrodes can be brought into contact with the upper portion of the slag bath, while being kept entirely away from the charge. I 35 prefer that in all cases the crucible shall have a depth greater than the diameter of the bottom opening of the shaft into the crucible. Also in the arrangement of the electrodes by which the maximum heating 40 effect is obtained within the body of the bath, the heat being uniformly distributed.

When the tri-phase electric current is used, the current connected to the different electrodes can be of different voltages, thus 45 forming means for accurately controlling and regulating the heat in different portions of the bath. I prefer to normally separate the upper and lower electrodes by vertical distances greater than the diameter 50 of the feed opening into the crucible, and that all the electrodes be at substantially equal distances from each other. By this arrangement of the electrodes, a much more uniform heating action can be obtained. 55 The cost of operation is greatly reduced, owing to the small consumption of electrodes, and any suitable carbonaceous material may be employed for the reduction of the charge, this, of course, being mixed with 60 the charge as it is needed, in the usual manner.

I do not desire to limit myself to the particular construction and arrangement of the parts which I have shown and described, as 65 various changes may be made therein with-

in the spirit and scope of the appended claims, without departing from my invention.

I claim:

1. An electric furnace having a shaft and an enlarged crucible at the base of the shaft, said crucible having a depth greater than the diameter of the bottom opening of the shaft into the crucible, upper and lower electrodes in the crucible, and means for maintaining a bath level in the crucible sufficiently high to cause it to surround and protect the portions of the upper electrodes which are within the crucible; substantially as described. 70

2. An electric furnace having a shaft and an enlarged crucible at the base of the shaft, said crucible having a depth greater than the diameter of the bottom opening of the shaft into the crucible, upper and lower electrodes in the crucible, the upper electrode being movable relatively to the lower electrode or electrodes, and means for maintaining a bath level in the crucible sufficiently high to cause it to surround and protect the portions of the upper electrodes which are within the crucible; substantially as described. 80

3. An electric furnace having a shaft and an enlarged crucible at the base of the shaft, said crucible having a depth greater than the diameter of the bottom opening of the shaft into the crucible, upper and lower electrodes in the crucible, the upper electrodes extending into the crucible at points 95 to one side of the shaft, and being movable vertically, and means for maintaining a bath level in the crucible sufficiently high to cause it to surround and protect the portions of the upper electrodes which are within the crucible; substantially as described. 100

4. An electric furnace having a crucible provided with a feed-in-opening at its top, and having at least two upper electrodes and at least one lower electrode, the upper and 110 lower electrodes being normally separated from each other by vertical distances greater than the diameter of said feed opening, all the electrodes being normally at substantially equal distances from each other; substantially as described. 115

5. An electric furnace having a crucible provided with a feed-in-opening at its top, said crucible having at least two upper electrodes and at least one lower electrode, which are all normally spaced at substantially equal distances from each other, and are connected to different conductors of a multi-phase circuit; substantially as described. 120

6. An electric furnace having a crucible provided with a feed-in-opening at its top, and having upper and lower electrodes, the upper and lower electrodes being separated from each other by vertical distances greater 130

than the diameter of said feed opening, and means whereby the bath in said crucible may be maintained at a level sufficiently high to completely surround the portions of the upper electrodes which are within the crucible; substantially as described.

7. An electric furnace having a crucible provided with a feed-in-opening at its top, said crucible having upper and lower electrodes, which are all normally spaced at substantially equal distances from each other,

and are connected to different conductors of a multi-phase circuit, the upper electrodes being out of contact with the charge which enters the crucible through said feed-in- 15 opening; substantially as described.

In testimony whereof, I have hereunto set my hand.

RAYMOND S. WILE.
